Primary Examiner — Khawaja Anwar(74) *Attorney, Agent, or Firm* — Quarles & Brady LLP(57) **CLAIM**

The ornamental design for an ice pack, as shown and described.

DESCRIPTION

FIG. 1 is an isometric view of a front, bottom, and left side of an ornamental design for an ice pack;

FIG. 2 is a front elevational view of the ice pack of FIG. 1; FIG. 3 is a rear elevational view of the ice pack of FIG. 1; FIG. 4 is a right side elevational view of the ice pack of FIG. 1;

FIG. 5 is a left side elevational view of the ice pack of FIG. 1;

FIG. 6 is a top plan view of the of the ice pack of FIG. 1; and,

FIG. 7 is a bottom plan view of the ice pack of FIG. 1. The dash-dash-dash lines are included for the purpose of illustrating portions of the ice pack that form no part of the claimed design. The dash-dot-dash broken lines are included for the purpose of illustrating boundary lines and form no part of the claimed design.

1 Claim, 5 Drawing Sheets(56)
